CARBURETER OR VAPORIZER FOR EXPLOSIVE ENGINES.

1,137,728.

Specification of Letters Patent.

Patented May 4, 1915.

Application filed April 9, 1904. Serial No. 202,309.

To all whom it may concern:

Be it known that I, EDWIN F. ABERNETHY, a citizen of the United States, residing at the city of New York, borough of Brooklyn, in the county of Kings and State of New York, have invented certain new and useful improvements in Carbureters or Vaporizers for Explosive Engines, and I do hereby declare the following to be a full, clear, and 10 exact description of the same:

A practical carbureter or vaporizer for internal combustion engines requires the uninterrupted supply of liquid fuel at or adjacent to the fuel inlet valve, because in the service of engines of this class the pressure in the supply tank varies with the fuel head or the changes in the level of the fuel supply, particularly in case the engine is of the stationary class. This is also true of engines designed for use on a motor vehicle or in a marine vessel, and in these cases the supply of fuel is not always owing to changes in the position or level of the vehicle or vessel, under the requisite head 15 or pressure to insure the inflow of fuel when the proper valve is open, because the movement of the vehicle or the vessel causes the fuel head to temporarily drop away from the fuel inlet.

The feature of the present invention resides in the provision of means in a liquid fuel carbureter or vaporizer by which a constant head and level of fuel is established and maintained at the fuel inlet so as to be 20 free from, or independent of, changes in the position or level of the vehicle or vessel, or of the head and pressure in the tank when used on stationary engines, and to thereby afford an invincible, unfailing supply of fuel on opening the fuel valve. In my improved device, there is maintained at all 25 times and under all conditions a certain volume of fuel at the inlet passage ready to flow under gravity pressure into the carbureting chamber immediately the fuel valve is opened, and this fuel is maintained at a constant level by the action of a float-controlled valve, the latter being opened automatically on the descent of the float 30

below a predetermined level, so as to replenish the supply and maintain the desired body or quantity of liquid at or above the fuel inlet, thereby securing the necessary head or pressure and insuring the prompt inflow of fuel under the action of certain parts of the vaporizer or carburetor.

A feature of the present invention resides in the provision of means by which the fuel is supplied to a mixture valve of the carbureter or vaporizer on the same side as the air is admitted thereto, that is to say, if the air is admitted to the underside of a mixture valve, the fuel supply is admitted also to the underside of the mixture valve, instead of admitting air to one side 45 of the valve and fuel on the other side of said valve, as is customary in some of the devices of this class. This secures an important advantage in a carbureter or vaporizer for an internal-combustion engine 50 wherein the supply of combustible vapor is drawn into the engine cylinder by a suction draft, because the fuel is supplied to the carbureter at a point where it is not under the direct influence of the suction draft and 55 the fuel is thus given an opportunity to become thoroughly mixed with the air as the latter is drawn through the carbureter, whereby a combustible mixture or vapor is 60 produced wherein the air is thoroughly impregnated with the fuel.

In my improved carbureter provision is made for regulating the volume of air and of fuel admitted at each opening movement of the mixture and the fuel valves so as to 65 produce a combustible mixture or vapor wherein the air and fuel are combined in proper proportions. The fuel valve is controllable by the movement of the mixture valve, although both valves are seated independently by separate retractors in the form of springs, and although the fuel valve is 70 adapted to move to a full opened position each time it is actuated by the mixture valve, provision is made for varying the tension on the mixture valve so as to govern 75 the extent or degree of the opening movement of both valves under the suction draft 80

on the mixture valve, whereby the carbureter under varying speeds or loads of the engine will supply a combustible mixture or vapor of uniform grade or quality to the 5 engine cylinder.

Further objects and advantages of the invention will appear in the course of the subjoined description, and the actual scope thereof will be defined by the annexed 10 claims.

The figure of the drawings is a vertical section of an automatic carbureter or vaporizer for internal-combustion engines constructed in accordance with my invention.

15 The construction shown embodies a casing, 5, which is divided by a partition or valve seat 6, into a suction chamber, 7, and a carbureting chamber, 8, said casing having an air inlet 9 to the carbureting chamber, 20 8, and a suction connection, 10, in communication with the chamber, 7.

A mixture valve or suction operated element, 11, is provided on its under side with a washer, 12, of leather or the like, and it 25 normally occupies the seat afforded by the partition, 6, to cut off communication between the chambers, 7, 8. Said valve has a depending stem consisting of a hollow portion, 13, and a solid portion, 14, and with 30 the stem is associated a baffle or spreader, 15, the stem and the baffle being movable or slideable with the mixture valve, 11. The baffle is of larger diameter than the stem; it is arranged at or near the line between the 35 hollow and solid portions of the stem, and it may be made in one piece with the stem or it may be attached thereto. Said spreader may be solid or imperforate, or it may be perforated for the passage of air and fuel, 40 as shown.

The lower part of the casing, 5, has a hollow nipple, 16, which is threaded internally, and into it is screwed an externally-threaded guide and adjusting sleeve, 17, the latter 45 being in axial alinement with the valve and slideably receiving the lower solid member, 14, of the valve stem. This sleeve is provided at its lower exposed end with a head, 18, which is always accessible for the purpose of adjusting the sleeve by hand, and on 50 the sleeve is screwed a check nut, 19, which binds against the casing, 5, and locks the sleeve against movement. The solid member, 14, of the mixture valve stem protrudes 55 below the headed end of the adjusting sleeve, 17, and on the lower extremity of the stem is a foot, 20, on which is seated a coiled spring, 21, the latter loosely encircling the stem and acting against the sleeve 17 so as 60 to place tension on the stem and the mixture valve. It is evident that the sleeve may be screwed into the casing to relax the tension of the spring and to place very light tension on the mixture valve, but by adjust-

ing the sleeve in a downward direction, it is 65 adapted to compress the spring and increase the tension on the valve, as may be desired.

One of the leading features of this invention resides in means for maintaining a head of fuel constantly at or above the fuel inlet, 70 irrespective of the position or level of the vehicle or the vessel on which the engine is installed. In the embodiment of this part of the invention I provide a chambered shell, 22, shown as having a detachable threaded 75 connection with the casing, 5, at the upper part thereof. The shell 22 provides a feed chamber, 23, above the suction chamber, 7, and fuel is supplied to this feed chamber from a tank or other available source of supply 80 by means of a feed pipe, 24. The cap, 25, of the shell 22 is provided with an inlet boss, 27, the latter having a vertical passage forming a valve seat and one or more fuel ports, 28. Said cap 25 is also provided with 85 an upstanding boss, to which is coupled the feed pipe, 24, and this boss has an air vent, 30, in communication with the chamber, 23, a vent pipe 31 extending a suitable distance above the carbureter to prevent the overflow 90 and waste of the fuel.

Fitted slidably in the opening forming the valve seat is a shut off fuel valve 29, which is in the form of a needle or spindle having a tapering end, and this valve is attached in a suitable way to the float, 39^a, which is arranged in the feed chamber 23 so as to have a limited rising and falling movement therein in order to automatically control the valve for establishing and maintaining a fuel head at a constant level in 100 a member or part of the carbureter or vaporizer.

From the bottom of the chamber 23 depends a fuel inlet tube, 32, which extends 105 into and terminates at a suitable point in the hollow member, 13, of the mixture valve stem, said mixture valve being slideable on the tube 32 and the solid member 14 of the stem being slideable in the sleeve, whereby 110 the mixture valve is limited by the stem 14 and the tube 32 to slideable movement in the chamber 7. The hollow member of the mixture valve stem has ports, 33, of suitable size, located just above the baffle 15, and 115 through these ports is adapted to flow the liquid fuel which is conducted from the chamber 23 by the tube 32 and thence through the hollow member of the valve stem to the spreader. By locating the 120 spreader below the mixture valve and arranging the fuel supply devices for conducting the fuel through the mixture valve and to the spreader, I am able to dispense with outside tubing or separate channels and to 125 admit the fuel to the carbureter on the same side of the mixture valve as the air is admitted to said valve. This allows the fuel

to be supplied to and diffused over the spreader in a way to be absorbed or "picked up" by the current of air, and without exposing the fuel to the suction draft from the engine, whereby the air and the fuel may be combined before entering the suction chamber of the carbureter.

The fuel tube 32 is provided with a valve seat, 34, for the accommodation of the fuel valve, 35, the stem 36 of which is prolonged through said tube, 32, and into the hollow member 13, of the mixture valve stem. Said stem, 36, is provided at its lower end with a nut 37, and around the stem is loosely fitted a coiled spring, 38, the latter finding resistance against the tube 32 and seated on the nut 37 to place the fuel valve 35 under tension and normally seat it in the tube 32. The lower end of the stem 36, terminates a slight distance above the spreader or solid member of the mixture valve stem, and when the stem and the spreader are raised by lifting the mixture valve, the stem 36 and the fuel valve are also raised, thus opening the passage through the tube 32 and permitting the fuel to flow from the feed chamber 23, through the tube, 32, the hollow member 13 of the mixture valve stem, the ports, 33, and diffuse itself over the spreader.

The float-controlled feed valve 29 maintains at all times a constant supply of liquid fuel and at a predetermined level in the feed chamber, 23, the quantity of fuel being sufficient to establish a head pressure of the fuel immediately at the fuel inlet valve 35, so that the fuel will at once flow into the carbureter on opening said valve, 35. The spring 21 is placed under the required tension, either light or strong, by proper adjustment of the sleeve or nut, 17, to interpose more or less resistance to the lift of the mixture valve, and of the fuel valve 35 which is controllable by said mixture valve.

With the engine in operation, a suction draft lifts the mixture valve 11 a distance proportioned to the resistance of the spring, 21, and the upward lift of said valve raises the fuel valve 35 a corresponding distance, so that the fuel is admitted below the mixture valve and in the path of the air, to be picked up thereby and intermingled therewith for the production of the combustible mixture or vapor. As the suction draft ceases, the valves, 11, 35, are seated promptly by the reaction of their respective springs.

The employment of means for varying the tension of the spring on the mixture valve is an important feature of my invention, because it provides means for regulating the lift of the mixture and the fuel valves, to regulate the quantity of fuel in proportion to the volume of air each time the valves are opened, and thereby secure

the production of a combustible mixture of a standard grade or quality. With a light spring tension on the mixture valve, the suction draft from the engine creates a partial vacuum in the chamber 7 and the pressure of air on the underside of the valve opens the latter to a wide open position, thus admitting a certain volume of air. On the upward movement of the mixture valve, the fuel valve 35 is unseated and moved for a distance substantially equal to that of the mixture valve, and thus a certain quantity of fuel is admitted to the chamber 8 proportionately to the air. By increasing the tension of the spring 21 on the mixture valve, the lift thereof due to the suction draft is decreased, and correspondingly the lift of the fuel valve is decreased so as to admit a proportionately less quantity of fuel to the chamber 8, but the supply of air is not decreased notwithstanding the decrease in the travel of the valve 11, because the air rushes into and through the chambers, 8, 7, at increased velocity. It is to be understood, therefore, that the adjustment of the spring tension on the mixture valve, 11, has the effect of regulating the admission of the fuel to the carbureter, although the mixture valve spring, 21, does not act on the fuel valve, 35, and the latter is seated by the action of an independent spring.

In my vaporizer, the valves, 11, 35, open upwardly and close downwardly, and the springs are shown as being arranged below the valves. This operation of the valves is advantageous, because in the event of breakage of the springs the valves will still operate and the carbureter will be suitable for service. The weight or gravity of the mixture valve and its parts will cause the valve to be seated when the suction draft ceases, while the gravity of the fuel valve and the pressure of the fuel head thereon insure the seating of said valve, thus overcoming the possibility of flooding the vaporizer.

The spreader 15 is movable with the mixture valve when it is lifted by the suction draft and the fuel is diffused over the surface thereof, such upward travel of the spreader interposing the same more directly in the path of air as it enters the carbureter and placing the fuel directly in the path of the air to be picked up and mingled therewith.

As hereinbefore described, one of the important features of my invention is the provision of means for maintaining a head of fuel at a constant level adjacent to the fuel valve and insuring the feed of the fuel under gravity to the carbureter, irrespective of changes of the position of the supply tank and the engine on a vehicle or a marine engine, or of the gradually changing level and pressure of the fuel in the tank when used

on stationary engines or in connection with engines of vehicles and marine vessels. This end is secured in my structure by the provision of the feed chamber 23 and a 5 means between the chamber and the source of supply by which the fuel is maintained at a constant level in the feed chamber so as to establish therein the requisite fuel head which has direct communication with the 10 fuel inlet when the valve 35 is unseated by the action of a suction operated element, usually the mixture valve, 11. It will be seen that the fuel is free to feed itself by gravity to the vaporizer when the fuel valve 15 is unseated, and when sufficient fuel escapes from the feed chamber to change the fuel level therein, the float 39^a, drops so as to partially withdraw the valve 29 and allow the fuel to be replenished in the chamber 20 23 by the feed pipe 24, after which the rise of the float closes the valve 29 and cuts off the further ingress of fuel to the chamber 23 on the establishment of the normal fuel supply to the required level. These operations 25 are wholly automatic, and the parts work in a positive manner so as to be efficient and reliable in service.

The particular means adopted by me for the maintenance of fuel at a constant level 30 and under the desired head in a feed chamber adjacent to a fuel inlet valve, may be modified by a skilled mechanic, and I do not, therefore, desire to strictly confine myself to the specific embodiment of the invention 35 herein shown and described.

Having thus fully described my invention, what I claim as new and desire to secure by Letters Patent is:—

1. A vaporizer or carbureter of the class 40 described comprising a carbureting chamber, a feed chamber positioned above the carbureting chamber, a fuel valve intermediate said carbureting and feed chambers, whereby liquid fuel may be supplied to the former 45 from the latter, means for conveying liquid fuel to the feed chamber, a float controlled valve operating within the feed chamber and adapted to shut off the flow of liquid into said chamber without disturbing the 50 communication between the carbureting and feed chambers, whereby a predetermined head of liquid fuel is maintained at all times in proximity to the valve intermediate the carbureting and feed chambers, and a 55 suction operated element for automatically opening said valve between the carbureting and feed chambers the liquid connection from the feed chamber to the carbureting chamber operating to discharge fuel below 60 the suction operated element.

2. A vaporizer or carbureter having a carbureting chamber, a feed chamber directly above the carbureting chamber, a vertical

tube affording a direct connection between the feed chamber and the carbureting chamber, a supply pipe connected to said feed chamber, a float and a valve in said feed chamber for maintaining therein a fuel head at a constant level above the vertical tube, a suction operated element, and a separate 65 fuel valve opened solely by said element for controlling the gravity inflow of fuel through said vertical tube, said vertical tube operating to discharge the liquid fuel below the suction operated element. 75

3. A vaporizer or carbureter having a carbureting chamber, a feed chamber positioned above the carbureting chamber, a mixture valve for varying the area of the air inlet to the carbureting chamber, a supply pipe 80 connected to said feed chamber for feeding fuel directly thereto, a float and a valve positioned within said feed chamber for maintaining in the feed chamber a fuel head at a constant level, a fuel valve seated independently of the mixture valve for controlling the communication between the two chambers, said fuel valve being opened by the mixture valve, and a spreader below the mixture valve, the fuel inlet to the carbureting chamber being at a point directly below the mixture valve and over the spreader. 90

4. A vaporizer or carbureter having a fuel valve, a mixture valve disconnected from said fuel valve and co-operating therewith 95 for operating said fuel valve, said valves being seated independently of each other, a resistance opposing the opening movement of the mixture valve, means for adjusting the resistance to impart variable travel to the 100 mixture valve and the fuel valve, means for conducting fuel through, and discharging it below, the mixture valve, and a spreader positioned below said mixture valve.

5. A vaporizer or carbureter having a 105 mixture valve, a fuel valve controllable thereby, said valves being seated independently of each other, means for placing tension on the mixture valve, means for conducting fuel below the mixture valve, and a 110 spreader movable with the mixture valve, said spreader being independent of the fuel valve.

6. A vaporizer or carbureter having a 115 mixture valve, a spreader movable with the mixture valve, a fuel valve separate from the mixture valve and the spreader and seated independently of said mixture valve, a tension device opposing the opening movement of the mixture valve, means for varying the resistance of the tension device, and means for conducting fuel below the mixture valve. 120

7. A vaporizer or carbureter having a carbureting chamber, a feed chamber above 125 said carbureting chamber, a mixture valve

means for admitting air to one side of the mixture valve, means for conducting fuel through the mixture valve and feeding the fuel to the same side of said mixture valve 5 that the air is admitted thereto, and a fuel valve separate from and controllable by the mixture valve.

8. A vaporizer or carburetor having a carbureting chamber, a feed chamber, a mixture valve to said carbureting chamber, a hollow stem leading through the mixture valve, means for supplying fuel from the feed chamber to said hollow stem, and a fuel valve separate from said carburetor by the mixture valve.

9. A vaporizer or carburetor having a carbureting chamber, a mixture valve, a hollow stem connected to the mixture valve, a spreader separate from the mixture valve 20 and carried by said hollow stem, means for conducting fuel through said stem and delivering it above the spreader, and a fuel valve.

10. A carburetor or vaporizer having a carbureting chamber, a mixture valve, a spreader in the carbureting chamber and below the mixture valve, and a fuel valve for supplying fuel to the spreader, a fuel being 25 carried below the mixture valve, and a fuel valve separate from the mixture valve and carried independently thereof, the fuel valve being operable by the movement of the mixture valve.

11. A vaporizer or carburetor having a carbureting chamber, a mixture valve, a fuel valve separate from the mixture valve and carried independently thereof, the fuel valve being carried by the mixture valve, a spreader positioned below and movable with 40 the mixture valve, said spreader and mixture valve being movable to a limited extent independently of the fuel valve and means for supplying variable pressure on the mixture valve.

12. A vaporizer or carburetor comprising a suction chamber, a feed chamber directly over said suction chamber, a supply pipe connected to said feed chamber, a supply valve located in said supply pipe, a fuel pipe connected to said feed chamber, a fuel valve located in said fuel pipe, a fuel valve located in said fuel pipe, a fuel valve being operated by said suction chamber, a fuel valve being operated by said feed chamber, a fuel valve being operated by said level, a float valve located in said suction and carbureting chamber, a valve for varying the area of the air inlet to said suction chamber, a vertical liquid tube leading from the feed chamber to a point below the mixture valve, and a fuel valve in the tubular connection between the two chambers, said fuel valve being operated by said mixture valve.

13. A vaporizer or carburetor comprising a suction chamber, a feed chamber, a supply

pipe connected to the feed chamber, a supply valve controlling the outlet from said pipe, a float in the feed chamber and operating the supply valve for maintaining in the feed chamber a fuel head at a predetermined level, a mixture valve exposed to a suction draft in the suction chamber, a vertical tube leading from the feed chamber to a point in the suction chamber below the mixture valve, and a slideable fuel valve in the aforesaid tube between the two chambers.

14. A carburetor or vaporizer comprising a suction chamber, a feed chamber, a supply pipe connected to the feed chamber, a supply valve controlling the outlet from said pipe, a float in the feed chamber and operating the supply valve for maintaining in the feed chamber a fuel head at a predetermined level therein, a mixture valve exposed to the suction in the suction chamber, means for conducting fuel from the feed chamber and discharging it below the mixture valve, a fuel valve separate from the mixture valve and operating in the said feed conducting means, said valve being sealed independently by a check valve movement in the suction chamber and the fuel inlet, respectively, and said fuel valve being opened by the suction operated mixture valve.

15. A vaporizer having a suction chamber provided with an opening for the admission of a combustible vapor thereto, a suction operated element in operable relation to said opening, a feed chamber, a vertical tube affording a direct connection from said feed chamber to a point below the suction operated element, and an automatic fuel valve for controlling the fuel inlet and when activated permitting the fuel to flow by gravity from the feed chamber.

16. A vaporizer having a carbureting chamber, a suction-operated element therein, a feed chamber having means arranged therein for maintaining a fuel head the level of which is constantly above the carbureting element, a vertical tube leading the carbureting chamber with the feed chamber for connecting said to the former, a float valve in the feed chamber, a fuel valve connected with said float valve and actuated independently of the float valve for regulating the quantity of fuel admitted to pass from the feed chamber to the carbureting chamber at each operating movement of the fuel valve.

17. A vaporizer having a carbureting chamber, a suction-operated element therein, a feed chamber, a vertical tube connecting said feed chamber with the carbureting chamber for conducting fuel to the latter below the suction-operated element, a fuel valve connected with said vertical tube and actuated independently of the float valve for regulating the quantity of fuel admitted to pass from the feed chamber to the carbureting chamber at each operating movement of the fuel valve.

means for regulating by hand the quantity of fuel adapted to pass from the feed chamber to the carbureting chamber at each opening movement of the automatic fuel valve.

18. A vaporizer having a carbureting chamber, a suction-operated element therein, a spring, means for regulating the tension of the spring on said element, a feed chamber, means in said feed chamber for maintaining therein a fuel head at a predetermined level above the carbureting chamber, a vertical tube affording a direct

connection between the feed chamber and the carbureting chamber and adapted to conduct fuel below the suction-operated element, and an automatic fuel valve operating in said vertical tube.

In testimony that I claim the foregoing as of my invention, I hereunto sign my name in the presence of two subscribing witnesses.

EDWIN F. ABERNETHY.
